ELECTRON DISCHARGE DEVICE

George Dean O'Neill, Beverly, Mass., assignor to
 Hygrade Sylvania Corporation, Salem, Mass.,
 a corporation of Massachusetts

Application April 26, 1935, Serial No. 18,353

9 Claims. (Cl. 250—27.5)

This invention relates to electron-discharge devices and more particularly to wave repeating or amplifying devices such as radio tubes or the like.

In certain types of radio tubes, particularly those which are used as voltage amplifiers, the dynamic "plate-resistance" is a very important factor and should preferably be maintained as high as possible for different values of plate voltage. In the case of those tubes having a shield around the plate, it has been found that with the usual type of construction when the anode voltage approaches the shield voltage, the dynamic plate resistance, due to the lowered plate-shield potential gradient, is materially lower than when the anode is at a substantially higher voltage than the shield. Consequently under these conditions, any change in plate current whether resulting from a change of primary or secondary electron flow to or from the plate, appears as a change in the dynamic plate resistance of the tube. When the potential gradient between the shield and plate is lowered, any small change in the plate voltage will produce an abnormally large variation in the plate current, which is equivalent to a lowered dynamic plate resistance.

Accordingly, one of the principal objects of this invention is to provide an arrangement for controlling the dynamic plate resistance of electron discharge tubes especially, although not necessarily, so-called voltage amplifier tubes.

A feature of the invention relates to a tube of the screened anode type, having means for minimizing the controlling influence of the alternating plate voltage upon electrons moving radially from the cathode or screen grid toward the edge of the plate.

Another feature relates to a tube of the screened-plate type wherein means are provided to control the secondary emission from the plate to the shield or from the shield to the plate in such a way as to increase the apparent dynamic plate resistance of the tube.

A further feature relates to a screened-plate radio tube having a specially designed shield whereby the screen and plate may be operated with relatively low voltage gradient therebetween, without correspondingly reducing the dynamic plate resistance of the tube.

A still further feature relates to the novel organization, arrangement and relative location of parts which go to make up an improved electron discharge repeater or amplifier of the screened-plate type.

Other features and advantages of the invention

not specifically enumerated will be apparent after a consideration of the following detailed description and the appended claims.

While the invention will be described herein as embodied in one particular type of tube, it will be understood that this is done merely for purposes of explaining the invention and not by way of limitation. Accordingly in the drawing,

Fig. 1 is a partial vertical sectional view of the upper portion of a tube mount embodying the invention.

Fig. 2 is a sectional view of the tube mount of Fig. 1 taken along the line 2—2 thereof.

Fig. 3 is a schematic diagram to explain the invention.

Referring to Figs. 1 and 2, the numeral 1 indicates any wellknown form of electron-emitting cathode comprising for example a tubular metal sleeve 2 on the exterior of which is an electron-emissive coating 3. Insulatingly mounted within the sleeve 2 is a heater filament 4 of any well-known construction. It will be understood of course that any other type of emitting cathode, such for example as a filamentary cathode, may be employed. Surrounding the cathode is a fo-

raminous control grid 5 which may be formed with a pair of side rods or uprights 6, 7, around which is helically wound the grid wire 8. Surrounding the control grid 5 is another similar grid 9 consisting of a pair of side rods or uprights 10, 11, 30

around which is helically wound the grid wire 13. Likewise a third grid 14 surrounds grid 9, grid 14 being formed with a pair of side rods 15, 16, around which is helically wound the grid wire 17. It will be understood that the various side rods or grid supports are fastened to, or otherwise supported in a suitable standard such as the usual reentrant press (not shown) in the manner for example as shown in Patent No. 1,950,456. Surrounding the cathode and grids is a tubular metal plate 18 which is fastened to a pair of side rods or supports 19, 20.

Surrounding the plate 18 is a screen consisting of a wire mesh cage 21 having fastened to its upper edge a metal cap member 22. The cap member 22 is provided with a transverse slot through 45 which pass the several side rods 6, 7, 10, 11, 15, 16, the slot having a transverse width greater than the diameter of the largest side rod so as to prevent short-circuiting of the various grids.

The plate 18 and the mesh cage 21 may be supported at their lower ends from the tube press in a manner similar to that in which the remaining electrodes are supported.

For the purpose of spacing the electrodes accurately from each other, and for preventing con-

tact of the grid side rods with the edges of the slot in cap 22, there is provided an insulator disc 23 of mica or other suitable material having a series of aligned perforations to receive the 5 cathode sleeve 2 and the various side rods described above. A similar mica disc may be positioned at the lower end of the mount to space the various electrodes apart in a similar manner, as indicated schematically in Fig. 3. For the purpose of spacing the outer screen 21 from the remaining electrodes, there are provided posts 24, 25 which pass through corresponding perforations in the spacer disc 23. The posts 24 and 25 are welded or otherwise fastened to struck up lugs 15 26, 27, in the cap member 22. For the purpose of supporting and spacing the entire mount at its upper end from the inner wall of the enclosing envelope, a series of insulator springs 28, 29, are inserted in the top cap member 22 the edges of 20 the springs 28 and 29 being adapted to engage flexibly the inner wall of the enclosing envelope in the manner described in detail in application Serial No. 700,638, filed December 2, 1933. Suitable lead-in wires are provided for the various 25 electrodes and preferably the lead-in wire 30 for the control grid 5 is taken out through the top of the tube.

With the above construction, it will be noted that since the outer screen including the members 30 21 and 22 substantially completely encloses the plate 18, it is necessary that the said plate 18 be shorter than the outer screen 21. When the tube above described is used in the usual way as a "pentode" the input signals are impressed in any 35 wellknown manner across the cathode 3 and the control grid 5. The grid 9 which may function as a shield grid has a suitable constant positive potential impressed thereon which potential is preferably lower than the potential impressed upon 40 the plate or anode 18. The grid 14 may function as the so-called suppressor grid and may be connected to the cathode 3 or may be maintained in any other manner at or near the cathode potential. With this arrangement, the primary electrons 45 that are emitted from the cathode 3 travel through the successive grids 5, 9 and 14 until they reach the plate or anode 18. When these primary electrons strike the screen-grid 9 secondary electrons may be released from the screen and 50 likewise when the primary electrons strike the plate 18 other secondary electrons may be released from the said plate. If the potential gradient between the screen-grid 9 and the plate 18 is sufficiently high, the majority of these secondary electrons will be attracted toward the plate 18 which 55 is more positive than the screen 9. In accordance with its usual function the suppressor grid 14 tends to prevent the secondary electrons from the plate reaching the screen-grid 9. Where the potential gradient between the plate electrode 18 and the outer screen 21 is relatively low an appreciable number of electrons, particularly those electrons 60 that are moving in a straight line to the edge of the plate, may have sufficient velocity to pass over the upper edge of the plate 18 to the outer shield 21. Consequently a slight change in the plate voltage by changing the potential gradient between the plate and shield will cause a disproportionate change in the number of electrons 65 which avoid the plate 18 and reach the shield 21. Furthermore the electrons which are released from the screen 13 and which are moving radially toward the edge of the plate 18 may with one potential gradient between the plate and shield 70 reach the plate while with another potential gra-

dient the same electrons may pass by the edge of the plate and eventually reach the shield 21. In order to overcome this condition there is mounted adjacent the edge of the plate 18 and preferably in contact therewith an annular insulating member 5 31 of mica or other suitable insulating material. As shown in the drawing the annular disc 31 is held in contact with the edge of the plate 18 by means of suitable lugs or swaged portions 10 32 on the plate side rods 19 and 20. Preferably the annular insulator member 31 extends inwardly 15 towards the suppressor grid 17 as indicated clearly in Fig. 2 of the drawing. If desired a similar annular insulator member 33 may be mounted in contact with the lower edge of the plate 18 as indicated schematically in Fig. 3 of the drawing.

The insulator disc 31 has a two-fold purpose: it prevents the escape of secondary electrons from the edge of the plate to the outer screen 21 or 20 the shield 22, and it serves to prevent the attraction to the plate 18 of electrons passing above the disc 31 or the escape over the edge of the plate of electrons passing under the disc. In like manner the disc 33, if used, serves to restrict to 25 the plate, electrons passing above the disc and to prevent those electrons passing below the disc from reaching the plate, and prevents the escape of secondary electrons from the plate 18 to the outer shield 21. It should be emphasized that 30 both the attraction of electrons and emission of secondary electrons are to be understood as the variation in these effects due to the alternating component of plate voltage. It has been found that by using the member 31 the undesirable 35 effects described are so minimized that, where the plate voltage is reduced to approximately that of the voltage on the screen 21, a substantial increase in the dynamic plate resistance of the tube is obtained. For instance with the plate 40 18 and the screen 13 at 100 volts positive with respect to the cathode, a five-fold increase in plate resistance was obtained over that obtainable without the member 31.

While one specific embodiment of the invention 45 is disclosed herein it will be understood that various changes and modifications may be made herein without departing from the spirit and scope of the invention. Thus while the drawing shows member 31 extending in a plane substantially perpendicular to the longitudinal axis of the mount if desired member 31 may be in the form of a cylindrical collar mounted to form an extension of the plate 18 it being understood that the edge of the insulating collar will preferably 50 be in close contact with the edge of the plate. 55

What I claim is:

1. In an electron-discharge tube, an electron-emitting cathode, a plate electrode, a control grid and a shield grid between said cathode and plate 60 electrode, said shield grid extending beyond the end of the plate electrode, an external screen for said plate electrode, and an insulator shield adjacent an edge of the plate electrode and extending only part way into the space between 65 the plate electrode and shield grid to reduce substantially the edge effect of said plate electrode upon the dynamic plate resistance of the tube.

2. In an electron-discharge tube, an electron-emitting cathode, a plate electrode, a control grid, 70 a shield electrode for the plate, said shield electrode comprising inner and outer members extending beyond the end of the plate electrode and a cap member substantially enclosing the plate electrode and in spaced relation thereto, 75

- and an annular insulator member mounted around the edge of the plate and extending only part way into the space between the plate and the inner shield member.
5. 3. A mount for a tube of the pentode type having inner and outer shielding electrode members for the plate electrode and extending beyond the end thereof, an annular insulator shield mounted adjacent one edge of the plate electrode and extending only part way into the space between the plate electrode and the suppressor grid, said insulator serving to reduce the edge effect of the plate electrode on electrons moving past the edge of said plate electrode.
10. 4. A pentode mount according to claim 3 in which the plate electrode of the pentode is foreshortened with respect to the outer shield electrode member and the annular insulator member is in contact with the edge of the plate electrode.
15. 5. In an electron-discharge tube, an electron-emitting cathode, a plate electrode, a plurality of grid electrodes between the cathode and plate electrode, an insulator disc for spacing said cathode and grid electrodes from each other, and another insulator disc mounted adjacent the edge of the plate electrode and through which said grid electrodes extend, said other insulator serving to reduce the edge effect of said plate on electrons moving past the edge of said plate.
20. 6. In an electron-discharge tube, an electron-emitting cathode, a control grid, a shield grid, a plate electrode, said shield grid extending beyond the end of said plate electrode and an annular ring of insulation in contact with the edge of the plate electrode and extending only part way from said plate electrode toward said shield grid to reduce the edge effect of said plate electrode on electrons moving past the edge of said plate.
25. 7. An electron-discharge tube according to claim 6 in which an outer shield surrounds the plate electrode and extends beyond the ends of said plate electrode.
10. 8. In an electron-discharge tube, an electron-emitting cathode, a plate electrode, a cup-shaped member enclosing said plate electrode and in spaced relation to the edge thereof, a shield grid electrode extending beyond the edge of said plate 15 providing a clear path for the passage of electrons past the edge of said plate to said screen electrode, and a ring of insulation in contact with the edge of the plate electrode to reduce the edge effect of said plate electrode on said electrons.
20. 9. In an electron-discharge tube, an electron-emitting cathode, a plate electrode surrounding said cathode, a shield electrode surrounding said plate electrode, said plate electrode being foreshortened with respect to said shield electrode, and insulator rings one in contact with each edge of the plate electrode to reduce the edge effect of said plate electrode on electrons moving past the edges of said plate electrode.
25. 30.

GEORGE DEAN O'NEILL.
